UNITED STATES PATENT OFFICE.

HARVEY F. DRAKE, OF ROCHESTER, NEW YORK.

POCKET CIGAR-SHIELD.

SPECIFICATION forming part of Letters Patent No. 717,556, dated January 6, 1903.

Application filed August 6, 1902. Serial No. 118,606. (No model.)

To all whom it may concern:

Be it known that I, HARVEY F. DRAKE, a citizen of the United States, residing at Rochester, in the county of Monroe, in the State 5 of New York, have invented an Improved Pocket Cigar-Shield, of which the following is a specification, reference being had to the accompanying drawings.

My invention relates to an improved pocket 10 cigar-shield designed more particularly for the protection of cigars while carried in the vest-pocket, but capable of being used for many other purposes and in different locations.

15 My invention is fully described and illustrated in the following specification and the accompanying drawings, the novel features thereof being specified in the claim annexed to the said specification.

20 In the accompanying drawings, representing my improved pocket cigar-shield, Figure 1 is an elevation. Fig. 2 is a side view. Fig. 3 is a top view.

25 My improved cigar-shield consists, essentially, of the flat or slightly-curved body A, having the bent sides or flanges B B' and the bottom or base C, the structure being without a back and adapted to receive and protect a number of cigars within it, as indicated 30 by the dotted lines.

The shield is made of any suitable material, such as fiber or celluloid, although I have found sheet-aluminium very suitable for the purpose.

35 The manner of inserting the shield in the pocket is shown in Fig. 3, the cloth being indicated by dotted lines. The shield may, however, be used with the body next the person of the wearer.

40 The cigars are confined laterally by the side flanges B B' and supported at their lower ends by the base C, and they are thus effectively protected while in the shield from accidental breakage, which so frequently happens to cigars carried loosely.

45 My improved pocket cigar-shield is simple, light, and cheap and entirely prevents injury to cigars carried in it.

I claim—

50 The herein-described pocket cigar-shield formed of a single piece comprising the body open at the top and entirely open on one side and having the bent flanges along two of its opposite edges, and the bent base at its lower edge substantially as and for the purposes set forth.

HARVEY F. DRAKE.
